15 Claims. (Cl. 178—44)

1

My invention relates to electron discharge devices and is concerned with such devices which have at least a pair of conductors passing from the exterior to the interior of the device and which are constructed to carry high frequency currents.

In order to maintain a vacuum or gas-tight envelope for the device, it is necessary that the conductors be associated with the device in a vacuum or gas-tight manner and for this purpose a seal is provided in contact with the conductors, the seal in most cases being the material of the envelope, if the latter is of insulating material, such as glass, or if the envelope of the device is of metal a separate seal of insulating material is employed.

The conductors for high frequency work are in the form of a transmission line, for example, a concentric line or a parallel wire system, and it is found with such a line that due to the dielectric constant of the material forming the seal being greater than the medium surrounding the conductors externally and internally of the envelope, the capacity per unit length in the seal of the conductors is not the same as that outside the seal. This causes the characteristic impedance of the part of the line forming the seal to be different from the characteristic impedance of other parts of the line, which gives rise to undesired reflections.

The object of the present invention is to provide an improved electron discharge device with a view to reducing the change in the characteristic impedance which occurs in the vicinity of the lead-in conductor seals.

According to the invention, an electron discharge device is provided having a transmission line comprising a pair of conductors passing from the exterior to the interior of the envelope of said device and in which the envelope is maintained vacuum or gas-tight by a seal in contact with said conductors and wherein, for the purpose of reducing the change of the characteristic impedance of said transmission line which would otherwise occur owing to the presence of said seal, one or both of said conductors is or are distorted in the region of said seal.

In one form of the invention one or both of said conductors is or are reduced in size in the region of the seal so as to offset the increase in capacity due to the presence of the seal, or, alternatively, said conductors are spaced farther apart in the region of said seal. The invention may be applied to conductors which form a concentric line or to conductors in the form of a

2

Lecher wire system, i. e., where the conductors comprise parallel wires or strips.

In order that the said invention may be clearly understood and readily carried into effect, it will now be more fully described with reference to the accompanying drawings in which:

Figure 1 is a longitudinal section of an electron discharge device embodying the invention,

Figure 2 is a longitudinal section taken 90° to Figure 1,

Figure 3 is a transverse section along the line 3—3 of Figure 2,

Figure 4 illustrates a modification of the arrangement shown in Fig. 2, and

Figures 5, 6 and 7 illustrate the invention as applied to an electron discharge device in which the conductors are in the form of concentric lines, the three figures illustrating different forms of seals.

20 The characteristic impedance Z_0 of a concentric transmission line is given by

$$Z_0 = \frac{138}{\sqrt{K}} \cdot \log_{10} \frac{r_1}{r_2}$$

25 where K is the dielectric constant, r_1 the inner radius of the outer conductor and r_2 is the radius of the inner conductor. It will be seen that if the dielectric constant K changes the characteristic impedance is no longer constant from point to point with the result that reflections and other undesired effects occur. The above equation applies only to concentric lines, but similar equations are known for conductors in the form of Lecher wire systems either where the conductors 30 of the system are circular wires or in the form of flat strips.

According to the invention it is possible to offset the change of the dielectric constant that occurs owing to the presence of the seal by distorting the conductors in the region of the seal either by reducing the dimensions of one or both of said conductors or by spacing the conductors farther apart.

40 Referring now to Figures 1, 2 and 3 of the drawings, the invention as shown in these figures is applied to conductors in the form of a Lecher wire system, the conductors being in the form of flat strips. The reference numeral 8 indicates the envelope of the device through which conductors 9 and 10 pass, these conductors being sealed through the envelope 8, the latter being assumed to be of glass, in any of the manners known in the art. The conductors 9 and 10 are in the form of flat strips, the conductor 9 being 45 connected to a grid 11 comprising two support

rods 12 and 13 around which the grid wire 14 is wound. The conductor 10 is connected to a flat cathode 15. The grid and cathode are of course arranged inside the envelope and high frequency currents are fed thereto by the conductors 9 and 10 from the exterior of the envelope, these high frequency currents being applied to the conductors from a concentric line comprising an inner conductor 16 connected to the conductor 9 and an outer conductor 17 connected to the conductor 10. An anode 11 is of course also part of the electrode assembly.

Since the characteristic impedance of the parallel wire system comprising the conductors 9 and 10 changes at the seal owing to the fact that the dielectric constant of the seal is different from the dielectric constant of the medium inside and outside the envelope, the increase in the capacity per unit length of the conductors which would otherwise occur is offset, according to the invention, by distorting one or both of the conductors where they pass through the seal.

In Figures 1 to 3, the conductors are distorted by reducing the area of both conductors 9 and 10 as indicated at 18. If desired, only the area of one of the conductors may be changed although it is preferred to decrease the area of both conductors. In this manner it is possible to make the characteristic impedance of the part of the transmission line which passes through the seal substantially the same as other parts of said line. Hence, reflections can be eliminated or substantially reduced.

Instead of reducing the area of the conductors, as shown in Figures 1 to 3, the spacing of the conductors can be increased in the vicinity of the seal and, as shown in the example of the invention illustrated in Figure 4, the conductors 9 and 10, where they pass through the envelope 8, are spaced wider apart compared with their separation both internally and externally of the envelope.

Although in the example shown in Figures 1 to 4 the Lecher wire system shown comprises flat strips, it will be understood that the invention can equally be applied to systems in which the conductors are in the form of wires of circular or other cross-section.

Figures 5 to 7 illustrate the invention as applied to a concentric line which is provided with a vacuum or gas-tight seal. Referring to Figure 5 of the drawings, the reference numeral 8 again indicates the envelope of an electron discharge device the concentric line passing through the envelope, the exterior of the outer conductor 19 of the line being sealed to the envelope 8 whilst between the inner conductor 20 and the interior surface of the outer conductor 19 a seal 21 is provided which serves to seal the interior of the concentric line thus ensuring a vacuum or gas-tight envelope. To offset the change of characteristic impedance that would otherwise occur due to the presence of the seal 21, either the internal diameter of the outer conductor 19 is increased, i. e.; the wall of the outer conductor is reduced in thickness, or the external diameter of the inner conductor is reduced, or both inner and outer conductors are so distorted. In the example shown in Figure 5 both the outer and inner conductors are so distorted and, as will be seen from the figure, the reduced portions of the inner and outer conductors project beyond the envelope 8 to the exterior thereof and these reduced portions are arranged to form one element of a plug and socket connection, thus facilitating the connection of a complementary con-

centric line to be attached thereto. Since with concentric lines high frequency currents are confined to the interior of the outer conductor, the dielectric constant of the envelope 8 which is sealed to the exterior of the outer conductor 19 does not affect the characteristic impedance of the line. The distortion of the conductors 19 and 20, therefore, only takes into account the change of characteristic impedance that is occasioned by the presence of the seal 21. The seal 21 need not lie in the same plane as the portion of the envelope 8 shown, but can be disposed in the manner shown, for example, in Figures 6 and 7.

15 Referring now to Figure 6 of the drawing, the seal 22 extends obliquely between the outer and inner conductors 19 and 20 and is in the form of a cone of insulating material suitably connected to the outer and inner conductors. The parts of the outer and inner conductors within 20 the planes bounding the length of the seal 22 are reduced, as shown, so as to avoid the change in capacity per unit length which would otherwise occur. Since the capacity effect of the seal 22 is greater at points nearer the inner conductor 20 than at points nearer the outer conductor 19, this effect can be compensated by progressively changing the thickness of the conductors 19 and 20 in the region of the seal. In the example shown, the diameter of the inner conductor 20 may be progressively reduced towards the smaller end of the seal 22 or, alternatively, or in addition, the internal diameter of the outer conductor 19 may progressively diminish towards the smaller end of the seal 22. Alternatively, the seal 22 may be of non-uniform thickness, whilst the conductors 19 and 20 may be reduced uniformly. It will be seen from Figure 6 that the seal 22 is displaced from the envelope 8. In Figure 7 the seal 22 is of substantially bell-shape 30 and the outer and inner conductors 19 and 20 are progressively reduced, as shown. Further reduced portions 23 and 24 are provided where the seal 22 is actually connected to the outer and inner conductors.

45 Although in the example shown in Figures 5 to 7, the outer and inner conductors are reduced, it will be appreciated that the invention can also be applied where the conductors are not reduced, 50 but in which the outer conductor is arranged farther from the inner conductor analogous to the arrangement shown in Figure 4. The concentric lines shown in Figures 5 to 7 may be connected interiorly of the envelope to conductors 55 in the form of Lecher wires similar to those shown in Figures 1 to 3. Where it is desired to feed more than two electrodes in an electron discharge device by a concentric line as, for example, in the case where a screening grid is provided in 60 addition to the control electrode and cathode shown in Figures 1 to 3, the outer conductor of the concentric line shown in any of the figures may be split longitudinally, the control electrode being connected to the inner conductor, the cathode to one of the sections of the outer conductor and the screening grid to the other section of the outer conductor. If desired, the conductors may be plated with silver or copper, including the portions of the conductors passing through 65 the seal so as to reduce losses. It is preferred in all cases that the length of each conductor passing through the seal is substantially the same.

70 While I have indicated the preferred embodiments of my invention of which I am now aware 75 and have also indicated only one specific applica-

tion for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. A device for use at ultra high frequencies and having an envelope and a transmission line comprising a pair of conductors passing from the interior to the exterior of the envelope of said device, both of said conductors extending through said envelope in which envelope a vacuum is insured by a seal in contact with said conductors, one of said conductors being formed so that the spacing between said conductors from one surface of the seal to the other surface of the seal is greater than at other portions of said conductors for reducing the change in the characteristic impedance of the transmission line through the seal.

2. A device for use at ultra high frequencies and having an envelope and a transmission line comprising a pair of conductors passing from the interior to the exterior of the envelope of said device, both of said conductors extending through said envelope in which envelope a vacuum is insured by a seal in contact with said conductors, one of said conductors having a portion of reduced size extending from one surface of the seal to the other surface of the seal for reducing the change in the characteristic impedance of the transmission line through the seal.

3. A device for use at ultra high frequencies and having an envelope and a transmission line comprising a pair of conductors passing from the interior to the exterior of the envelope of said device, both of said conductors extending through said envelope in which envelope a vacuum is insured by a seal in contact with said conductors, said conductors being spaced farther apart in the region of the seal for reducing the change in the characteristic impedance of the transmission line through the seal.

4. A device for use at ultra high frequencies and having an envelope, and a transmission line comprising a pair of conductors passing from the interior to the exterior of the envelope of said device, both of said conductors extending through said envelope in which envelope a vacuum is insured by a seal in contact with said conductors, said conductors comprising a concentric line, one of said conductors being distorted in the region of the seal for reducing the change in the characteristic impedance of the transmission line through the seal.

5. A device for use at ultra high frequencies and having an envelope containing electrodes, and a transmission line comprising a pair of conductors connected to said electrodes and passing from the exterior to the interior of the envelope of said device, both of said conductors extending through said envelope in which envelope a vacuum is insured by a seal in contact with said conductors, said conductors comprising a concentric line, the inner of said conductors being reduced in diameter and the inside diameter of the outer conductor being increased at said seal, and a cooperating coaxial line having an inner conductor recessed to receive the inner conductor through said seal, and a recessed portion on the outside of the outer conductor for receiving the outer conductor passing through said seal.

6. A device for use at ultra high frequencies and having an envelope containing electrodes, and a transmission line comprising a pair of conductors connected to said electrodes and passing from the exterior to the interior of the envelope of said device, in which envelope a vacuum is insured by a seal in contact with said conductors, said conductors comprising a concentric line, said seal between the outer and inner conductors extending obliquely therebetween, one of said conductors being progressively reduced in diameter toward said seal for deducing the change in the characteristic impedance of the transmission line through the seal.

10. 7. A device for use at ultra high frequencies and having an envelope containing electrodes, and a transmission line comprising a pair of conductors connected to said electrodes and passing from the exterior to the interior of the envelope of said device, in which envelope a vacuum is insured by a seal in contact with said conductors, said conductors comprising a concentric line, said seal between the outer and inner conductors extending obliquely therebetween, one of said conductors being progressively reduced in diameter toward said seal, and the other of said conductors being progressively increased in diameter inversely to said first conductor.

15. 8. A device for use at ultra high frequencies and having an envelope, and a transmission line comprising a pair of concentric conductors passing from the exterior to the interior of the envelope both of said conductors extending through said envelope, in which envelope a vacuum is insured by a seal in contact with said conductors, the inner of said conductors being reduced in diameter and the inside diameter of the outer conductor being increased at said seal.

20. 9. A device for use at ultra high frequencies and having an envelope containing electrodes, a transmission line comprising a pair of conductors connected to said electrodes and passing from the interior to the exterior of said envelope, said envelope being evacuated and a seal in contact with said conductors, said conductors comprising a concentric line, the inner of said conductors being reduced in diameter and the inside diameter of the outer conductor being increased at said seal, said seal comprising a cone-shaped member, the small inner end being sealed to the inner conductor at the reduced diameter and the larger end being sealed to the outside conductor at the increased inner diameter.

25. 10. A coaxial terminal assembly comprising a dielectric means, tubular coaxial line portions approaching the dielectric means at opposite ends, a central rod through the dielectric means axially disposed with respect to both said coaxial line portions, said dielectric means having one part thereof sealing one of the coaxial line portions and having a part of greater diameter than said one part, and conductive means overlying said dielectric means and connecting said tubular coaxial line portions, said dielectric means with said overlying conductive means and portion of rod therein having a surge impedance substantially equal to the surge impedance of the coaxial line portion adjacent said dielectric means.

30. 11. A coaxial terminal assembly having a tubular portion and a coaxial rod, a bead sealing said tubular portion with the rod projecting through said bead, and providing therewith a surge impedance discontinuity in the line, and means for increasing the effective diameter of the bead and 35. surge impedance to substantially equal the surge

impedance between the tubular portion and rod adjacent said bead.

12. A coaxial terminal assembly comprising a dielectric means, tubular coaxial line portions approaching the dielectric means at opposite ends, a central rod through the dielectric means axially disposed with respect to both said coaxial line portions, said dielectric means sealing one of said coaxial line portions and having a greater diameter than the inner diameter of said one of said tubular coaxial line portions, and conductive means overlying said dielectric means and connecting said tubular coaxial line portions, said dielectric means with said overlying conductive means and portion of rod therein having a surge impedance substantially equal to the surge impedance of the coaxial line portion adjacent said dielectric means.

13. A coaxial line assembly comprising a tubular member, a rod coaxially mounted therein, a dielectric member sealing said tubular member with said rod extending through said dielectric member, and means for increasing the effective diameter of said dielectric member and the surge impedance of the assembly at said dielectric member to substantially equal the surge impedance between the tubular member and the rod adjacent said dielectric member.

14. A coaxial terminal assembly comprising a dielectric member, two tubular conducting members extending in opposite directions from the dielectric member, a central conductor sealed through said dielectric member and axially disposed with respect to both said tubular members, said dielectric member sealing one of said tubular members, said one of said tubular members having a portion of increased internal diameter extending over said dielectric member and connected to the other of said tubular members,

said dielectric member with said extending portion and the portion of said central conductor enclosed therein having a surge impedance substantially equal to the surge impedance of said one tubular member and said central conductor adjacent said dielectric member.

15. A device for use at ultra high frequencies and having an envelope and a transmission line comprising a pair of conductors passing from the interior to the exterior of the envelope of said device, both of said conductors extending through said envelope in which envelope a vacuum is insured by a seal in contact with said conductors, both of said conductors having a portion of reduced size extending from one surface of the seal to the other surface of the seal for reducing the change in the characteristic impedance of the transmission line through the seal.
